TOY GUN

Mark Winans, New York, N. Y.

Application March 14, 1945, Serial No. 582,630

1 Claim. (Cl. 46—191)

1

This invention relates to new and useful improvements in a toy gun.

This is a refile of my original application filed November 27, 1943, Serial Number 511,933.

More specifically, this invention proposes the construction of a toy gun characterized by a member simulating a gun barrel and stock and which is provided with a recess at the trigger area within which a toy cricket having a resilient and flexible noise-making blade is disposed in a manner to have its blade flexed to make a noise simulating the report of a conventional gun.

Another object of the invention proposes the provision of a trigger mounted upon a support positioned across the open side of the recess and which has an inner arm engaging the blade of the cricket for flexing the same when the trigger is pivoted.

Still another object of the invention proposes arranging the device so that the resiliency of the flexible blade will be employed in a manner to return the trigger to its normal position after it has been flexed.

A further object of the invention proposes the provision or a means for adjustably mounting the cricket longitudinally relative to the trigger so that its position with relation to the trigger may be adjusted to be flexed more easily by the trigger.

It is a further object of this invention to construct a toy gun which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a toy gun constructed in accordance with this invention.

Fig. 2 is a longitudinal vertical sectional view of a portion of Fig. 1.

Fig. 3 is an enlarged partial horizontal sectional view taken on the line 3—3 of Fig. 1.

Fig. 4 is a partial horizontal sectional view taken on the line 4—4 of Fig. 1.

Fig. 5 is an end elevational view looking in the direction of the line 5—5 of Fig. 1.

Fig. 6 is a view similar to Fig. 2, but illustrating a modification of the invention.

The toy gun, according to this invention, includes a member 10 having a separate gun barrel 11 and

2

gun stock 12. These parts are securely attached together by several screws 13 extended between these parts. The gun stock 12 is formed with a recess 14 in the vicinity of its trigger area.

5 A support member 15 formed with an integral trigger guard 16 is mounted across the open side of the recess 14. The support member is secured in position by several screws 17 which pass through openings in the end of the support 15 and which are threadedly engaged into the gun stock 12.

One of the screws 13 may extend above the barrel and simulate a gun sight.

15 A toy cricket 18 is disposed within the recess 14 and is formed with a flexible and resilient blade 19. The blade when it is flexed is capable of making a noise similar to that of the report of a conventional gun. The resiliency of the blade restores it to its normal starting position after it 20 has been flexed.

A trigger 20 is pivotally mounted on the support 15. This trigger 20 is formed with an inner arm 21 which extends along the blade 19 of the cricket 18. Thus, when the trigger 20 is pulled 25 in the conventional manner, the free end of its arm 21 will move upwards and flex the blade 19 to make the gun noise. When the trigger is released the resiliency of the blade 19 will return the blade, the trigger 20 and the arm 21 back to their normal position as shown in Fig. 2.

The junction of the trigger 20 and the arm 21 is pivotally supported upon a pin 22 extended between a pair of spaced lugs 23 formed on the inner face of the support 15. The trigger 20 35 extends from the recess 14 through an opening 24 formed in the support 15 between the adjacent face of the lugs 23.

The front end of the gun barrel 11 has a cap 25 made of metal, plastic or other material 40 mounted thereon and secured in position by means of a single screw 26. The top of the cap 25 is formed with a sight 27, and the front face of the cap has several spots 28 painted thereon or 45 drilled to simulate that the gun barrel has several openings. The gun may also be manufactured without the cap 25, and a screw used as a sight.

A detailed operation of the gun is not believed 50 to be necessary as it is believed that those versed in the art will be fully aware of the manner in which the gun operates.

In Fig. 6 a modification of the invention is illustrated in which means is provided for adjusting the position of the cricket 18 longitudi-

3

dinarily with relation to the arm 21 of the trigger 20.

This means is characterized by a bracket 30 formed on the inside face of the support 15 and through which the front end of the cricket 18 is 5 slidably extended. A clamp screw 31 is threadedly engaged through a portion of the bracket 30 and is engageable against the cricket 18 for locking it in position on the bracket. Shifting the position of the cricket 18 causes the free end of its blade 19 to be adjusted with relation to the arm 21 to vary flexing of the blade 19 when the trigger 20 is pulled and thus change the noise that will be produced by the blade.

Adjusting the position of the cricket 18 may 15 be accomplished by removing the support 15 from the gun stock 12 to expose the clamp screw 31.

In other respects this form of the invention is similar to that previously shown and like reference numerals identify like parts in each of the 20 several views.

While I have illustrated and described the preferred embodiments of my invention, it is to be

4

understood that I do not limit myself to the precise constructions herein disclosed and the right is reserved to all changes and modifications coming within the scope of the invention as defined in the appended claim.

Having thus described my invention, what I claim as new and desire to secure by United States Letters Patent is:

A toy gun, comprising a member simulating a gun barrel and stock and having a recess formed at the trigger area, a trigger guard and support mounted across said recess, a toy cricket disposed within said recess and having a resilient and flexible noise-making blade, and a trigger pivotally mounted on said guard and support and having an inner arm engaging said blade for flexing the same when the trigger is pulled, whereby said blade will move said trigger forwards when said trigger is released, and means for longitudinally adjustably mounting said cricket on said trigger guard and support.

MARK WINANS.
